UNITED STATES PATENT OFFICE.

DANIEL D. WESSELS, OF DETROIT, MICHIGAN.

MOLDED RECEPTACLE.

1,399,174.

Specification of Letters Patent.

Patented Dec. 6, 1921.

Application filed November 29, 1920. Serial No. 427,029.

To all whom it may concern:

Be it known that I, DANIEL D. WESSELS, a citizen of the United States of America, residing at Detroit, in the county of Wayne 5 and State of Michigan, have invented certain new and useful Improvements in Molded Receptacles, of which the following is a specification, reference being had therein to the accompanying drawings.

10 The invention relates to metallic rims for molded receptacles, such as concrete laundry tubs, kitchen sinks, etc. Heretofore, it has been usual to form these metallic rims by beveling the ends of the rim parts, soldering 15 the beveled ends, laying the frame thus formed in the mold, then pouring concrete into the mold and upon the frame. This soldering operation involves a considerable expense and furthermore there is always a 20 liability that the rim parts may be tilted so that their faces will not be parallel due to the fact that the frame may not properly fit in the mold. It is the object of my invention to provide a metallic rim, the parts 25 of which can be easily engaged with each other to interlock, and further can be adjusted relative to each other to properly fit within the mold. Other objects of the invention reside in the novel features of construction and combinations and arrangements of parts as more fully hereinafter set forth.

In the drawings:

Figures 1 and 2 are top plan views of the 35 blanks of the coöperating members forming a corner of the rim;

Fig. 3 is a bottom plan view of a corner of the rim;

Figs. 4 and 5 are respectively cross sections on the lines 4—4 and 5—5 of Fig. 3;

Fig. 6 is a perspective view of a corner portion of a concrete laundry tub with my rim in place.

1 is a laundry tub preferably formed of 45 molded concrete and also having a metallic rim around its outer edge for protecting the same. 2 and 3 are coöperating members of the metallic rim which together form a corner at the outer edge of the tub, these 50 members being formed from blanks bent on the dotted lines shown in Figs. 1 and 2. The member 2 has the top 4 and the depending outer and inner side flanges 5 and 6 respectively which terminate in inwardly and 55 downwardly extending flanges 7 which latter are embedded in the concrete. The mem-

ber 3 has the top 8 and the depending front and rear side flanges 9 and 10 respectively, the flange 9 terminating in the inwardly and downwardly extending flange 11, while the flange 10 inclines inwardly and downwardly.

For the purpose of locking these members 2 and 3 to each other so that they will remain in proper position while the concrete 65 is being poured into the mold, the inner flange 10 of the member 3 is provided with the opening 12 and the open ended opening 13 adjacent to the under-surface of the top 8. The member 4 has the cut-away portion 70 14 forming the spaced bearings or tongues 15 and 16 which are adapted to extend through the openings 13 and 12 respectively and adjacent to the under surface of the top 8. The tongue 15 is at the outer edge 75 of the top 4 and the outer side 5 of the member 2 is adapted to substantially close the end of the member 3 when the two are assembled. 17 is a shoulder in substantial alignment with the inner end 18 of the cut-away portion 14, which shoulder is adapted to contact with the inner flange 10 of the member 3 to position the member 3 at right angles to the member 2.

To permit of moving the member 3 transversely of the member 2, the openings 12 and 13 in the member 3 are of greater length than the width of the bearings or tongues 16 and 15 respectively of the member 2. Since the bearings or tongues are longitudinally movable into the openings, it is seen that the members 2 and 3 may be relatively 90 adjusted to properly fit within molds of limited varied sizes. When pouring the concrete into the mold, the members forming the rim are inverted so that the concrete 95 will force the upper member downwardly upon the lower member and into firm contact therewith. The inwardly and downwardly extending flanges of these members 100 are embedded in the concrete to more securely hold the members in place.

From the above description, it will be readily seen that I have provided a simple construction of metallic rim for molded receptacles which has its parts mechanically locked firmly together due to the spaced bearings and in which the operation of soldering is eliminated.

What I claim as my invention is:

1. In a metallic rim for molded receptacles, the combination with a member hav-

ing a depending flange with an opening 5 therein, of a second member extending transversely to said first mentioned member and having a tongue slidably engaging in said opening.

2. In a metallic rim for molded receptacles, the combination with a member having a top and depending side flanges at its opposite edges, one of said side flanges having spaced openings therein adjacent to the 10 under surface of said top, of a second member having a top and depending side flanges at its opposite edges, said top having portions slidably engaging in said openings.

3. In a metallic rim for molded receptacles, the combination with a member having a top and depending side flanges, one of said side flanges having an open-ended opening and an adjacent opening therein near 20 said top, of a second member having a top and depending side flanges, one of said side flanges substantially closing the end of said first mentioned member and the top of said second member having a cut-away portion 25 forming bearings insertible through said openings and into engagement with the under surface of the top of said first mentioned member.

4. In a molded receptacle, a metallic rim

comprising members extending transversely 30 of each other and provided with coöperating superposed interlocking portions, said members also having portions anchored in the material forming the molded receptacle whereby said members are held in rigid 35 relation to each other.

5. In a molded receptacle, a metallic rim comprising members extending transversely 40 of each other and provided with coöperating inter-engaging portions for positioning the members at right angles to each other and for securing the members to each other while the receptacle is being molded, said members having anchoring portions molded within the material forming the receptacle 45 whereby the members are held in rigid relation to each other.

6. In a molded receptacle, a rim comprising 50 transversely extending members provided with coöperating bearing portions arranged to initially permit of limited relative adjustment of said members, said members also having portions anchored in the material forming the molded receptacle whereby said members are solely held in 55 rigid relation to each other.

In testimony whereof I affix my signature.

DANIEL D. WESSELS.
